UNITED STATES PATENT OFFICE.

JOHN MARCH, OF PHILADELPHIA, PENNSYLVANIA.

COLLAPSIBLE FAN.

Application filed February 10, 1925. Serial No. 8,199.

To all whom it may concern:

Be it known that I, JOHN MARCH, formerly a subject of the Emperor of Germany (having declared his intention to become a citizen of the United States), a resident of Philadelphia, county of Philadelphia, State of Pennsylvania, have invented certain new and useful Improvements in Collapsible Fans, of which the following is a specification.

The present invention relates to fans and more particularly to collapsible fans.

Some of the objects of the present invention are to provide a fabric fan in which the frame and cover can be readily separated; to provide an improved frame for distending and holding a fabric fan cover in operative condition; to provide a fan handle having a relatively movable part connected to a resilient frame for insertion in a bag-like cover to form a fan; to provide a fabric fan in which the fabric cover or body can be removed readily for laundering purposes; to provide a collapsible frame arranged to receive a cover having a contour corresponding to the frame in its expanded position; and to provide other improvements as will hereinafter appear.

In the accompanying drawings, Fig. 1 represents a side elevation of a collapsible fan embodying one form of the present invention; Fig. 2 represents a section on line 2-2 of Fig. 1; Fig. 3 represents a side elevation of the fan frame in open or operative position; and Fig. 4 represents a side elevation of the fan frame in collapsed position.

Referring to the drawings, one form of the present invention consists of a handle 10 formed as a rod of suitable shape, size and length, and having one end thereof provided with a slot 11. The frame proper consists in the present construction of two lengths of spring wire or rod 12, one end of each being looped for free movement about a pin 13 rigidly secured transverse of the slot 11. The position of the pin 13 is such that the end of the handle 10 lies in the arc of the wire 12 in order to form an uninterrupted curve when the frame is provided with its cover 14. The other ends of each of the frame wires are connected respectively to opposite ears 15 of a tubular member 16 which is arranged to slide freely upon the handle 10, it being understood that the handle passes through the member

10 so that the member 16 can be moved along the rod 10 to bring the frame to either expanded or collapsed condition.

The cover 14 is preferably formed of fabric having a contour simulating a fan shape and of such proportions as to be distended to that shape by the frame wire 10 when the latter has been duly expanded to operative position. As here constructed, the cover 14 is made of two like-shaped pieces of fabric joined by a seam 17 extending about the circumference except for the portion 18 which is left open for the insertion of the frame 12 and rod 10.

It will thus be evident that the fan is made up of two separable parts, one the fabric cover and the other the handle and frame. The latter, in its collapsed condition, is shown in Fig. 4, and it will be noted that the frame wires are substantially straight and lie parallel to and in close proximity to the handle 10. In this collapsed condition, the width of the handle and its frame is less than the width of the opening 18 in the fabric cover, and consequently in assembling the fan the pivoted end of the frame and the handle end can be readily inserted through the opening 18 and moved into the fabric until the end abuts the central portion of the opposite side or top of the fabric cover. When the handle has reached this position the member 16 is moved along the handle 10 toward the pivoted end of the frame, and thus causes the frame wires to swing outwardly in opposite directions about the pin 13 as a pivot, and as the two sides of the frame diverge, they engage the sides of the fabric cover and cause the latter to be distended until the frame assumes a shape corresponding in contour to the shape of the fan cover.

When this takes place, the member 16 has reached a point substantially at the opening 18, and the cover has been drawn taut, as shown in Fig. 1, by the expanded frame. The lateral expansion of the frame wires within the cover is such as to place them under tension, and acts in a direction which counteracts any tendency of the member 16 to move in a direction which ordinarily would collapse the fan. Thus the frame and its parts not only form a simple and effective collapsing device by which the fan can be taken apart, but also provide an effective natural reaction between the cover and frame which maintains the fan in its

open taut operative condition. It will be understood that the cover 14 and handle parts are not secured together in so far that they are held by the tension of the frame 5 wire when the latter is distended.

It will now be apparent that a complete operative collapsible fan construction has been provided, which is simple in construction, consists of few parts, and which can 10 readily be collapsed for convenient carrying purposes, and can just as readily be expanded into operative position for use.

Having thus described by invention, I claim:—

- 15 1. In a fan construction, a handle, a collapsible frame pivoted to one end of said handle at one part and slidably connected to said handle at another part, and a cover arranged to fit over said frame in collapsed condition and to be distended in fan shape in operative position of said frame.
- 20 2. In a fan construction, a handle, a collapsible frame comprising wires of spring material fastened at one end to said handle and 25 and a member slidable on said handle and

connected to the other end of said wires, and a cover arranged to fit over said frame in collapsed condition and to be distended in fan shape in operative position of said frame.

3. In a fan construction, a handle, a fan-shaped cover arranged to receive an end of said handle, and means carried by said handle for distending and holding said cover taut in fan shape.

4. In a fan construction, a handle, a fan-shaped cover arranged to receive an end of said handle, and means including a spring frame for distending and holding said cover taut in fan shape.

5. In a fan construction, a handle, a fan-shaped cover arranged to receive an end of said handle, and means including a spring frame and a part slidable on said handle for distending and holding said cover taut in fan shape.

Signed at Philadelphia, county of Philadelphia, State of Pennsylvania, this 30th day of September, 1924.

JOHN MARCH.
